CLAIM

The ornamental design for a display screen with dynamic graphical user interface, as shown and described.

DESCRIPTION

FIG. 1 is a front view of the display screen with dynamic graphical user interface showing a first image in a sequence; FIG. 2 is a front view showing a second image in the sequence;

FIG. 3 is a front view showing a third image in the sequence; FIG. 4 is a front view showing a fourth image in the sequence; and,

FIG. 5 is a front view showing a fifth image in the sequence. The outermost dash-dash double broken line rectangle illustrates a display screen and forms no part of the claimed design. The remaining broken lines show portions of the graphical user interface that form no part of the claimed design.

The subject matter in this patent includes a process or period in which an image changes into another image. This process or period forms no part of the claimed design.
